UNITED STATES PATENT OFFICE

CARL SCHWARZ AND PAUL PANHORST, OF PHILADELPHIA, PENNSYLVANIA

ADJUSTABLE FORM FOR MAKING PAPER BOXES

Application filed October 5, 1929. Serial No. 397,521.

Our invention relates to new and useful improvements in adjustable forms for making paper boxes and has for its object to provide a form of this description in which a plate of given dimensions is used for attachment to the reciprocating head of the machine and upon which the adjustable members are secured.

A further object of the invention is to provide for the various adjustments necessary to produce boxes of various sizes and to accomplish these adjustments in a simple and effective manner.

A further object of the invention is to provide for the vertical adjustment of the form relative to the head of the machine by which it is carried so as to facilitate the making of boxes of different depths without the use of fillers.

20 A still further object of the invention is to provide an adjustable platen for coacting with the adjustable presser plate.

With these and other ends in view, this invention consists in the details of construction and combination of elements hereinafter set forth and then specifically designated by the claims.

In order that those skilled in the art to which this invention appertains may understand how to make and use the same, we will describe its construction in detail, referring by numerals to the accompanying drawings forming a part of this application, in which:

35 Fig. 1 is a plan view of the assembled form.
Fig. 2 is an edge view of Fig. 1.

Fig. 3 is a section at the line 3—3 of Fig. 1.
Fig. 4 is a section at the line 4—4 of Fig. 1.
Fig. 5 is a perspective of the suspension

40 plate.
Fig. 6 is an elevation of the adjustable extension device to which the presser plate is attached.

Fig. 7 is a section at the line 7—7 of Fig. 6.

45 Fig. 8 is a bottom plan view of the presser plate showing the extensions thereof in dotted lines.

Fig. 9 is an edge view of Fig. 8.
Fig. 10 is a plan view of one of the exten-

50 sion angle members.

Fig. 11 is an edge view of Fig. 10.

Fig. 12 is a central section of the form showing the presser plate in proper relative position thereto and also showing in elevation the platen against which the presser plate is adapted to force and hold the bottom of the box during the manufacture thereof.

Fig. 13 is a plan view of a portion of the platen showing one of the slide plates adjustably secured thereon.

Fig. 14 is a section at the line 14—14 of Fig. 13.

In carrying out our invention as herein embodied, 15 represents a suspension plate upon the center of which is secured the block 16 by means of the screws 17 over the central opening 18 formed in the plate and this block has an opening 19 therein coinciding with the opening 18 for the purpose hereinafter set forth.

20 20 represents the suspension rods which are secured in the holes 21 formed in the block 16 and these rods are adapted to be attached to the head of the box making machine in any known manner as indicated in Fig. 1 of the patent to Smith and Reifsynder, No. 1,274,801, dated August 6, 1918.

25 22 represents the adjustable form which we prefer to make of three layers of metal and this form is composed of the angular sections 23 and 24, the sections 23 having their central layers shortened so as to form the grooves 25 while the sections 24 have their central layers extended so as to form the tongues 26, thus permitting the extension or contraction 30 of these sections relative to each other so as to adjust the completed form to the dimensions desired, as will be readily understood. These sections are held in any adjustment by the screws 27 which pass through the two upper layers of the sections and are threaded into lower layers as indicated at the right of Fig. 2.

35 Projecting from the central layers of each of the corner sections are the lugs 28 slotted as at 29 for the passage of the bolts 30 which bolts also pass through the slots 31 formed in the suspension plate and this arrangement provides for accommodating the adjustment of the form which is accomplished by loosening the bolts 30 while the form is being ad-

justed to any given dimensions and thereafter tightening up upon these bolts so as to bind the lugs against the suspension plate and thus hold the entire device as a unitary structure.

- 5 32 represents the presser plate to which the stem 33 is secured by the screws 34 passing through the flange 35 of said stem and this stem is internally threaded for the reception of the threaded suspension rod 36, the latter 10 being held in any adjustment relative to the stem by the jam nut 37. The upper end of the suspension rod 36 is removably mounted in the plunger of the box-making machine as usual. This presser plate has formed there- 15 in the slots 38 through which the set screws 39 pass, said screws being secured in the extension wings 40 thereby providing for the adjustment of said wings and the securement thereof in any adjustment, by the nuts 39a 20 run upon said screws.

The extension wings 40 are beveled as indicated at 42 so that when these wings are contracted to the smallest dimensions these beveled edges will abut and when adjusted to larger dimensions, as shown in dotted lines in Fig. 8, only a relatively small gap will be formed between these beveled edges.

In Fig. 12, we have shown the relation of the presser plate to the adjustable form when 30 the two are mounted upon a box making machine, and when so mounted in operation, the unfinished boxes one after the other are passed upward over the presser plate so that the downward movement of the rod 36 will carry 35 the bottom of the box into contact with the platen 43 of the machine and during this movement, the paper for covering and finishing the box having previously been attached to the under side thereof will be turned upward and 40 attached to the sides of the box by the action of the rolls of the machine, said rolls not being here shown as they are parts of the standard box making machines.

After the box has been seated upon the 45 platen, the bending fingers of the machine turn in the upper edges of the paper over the upper edges of the box and after the withdrawal of these fingers, the adjustable form passes into this box turning the paper down- 50 ward and dwelling a sufficient length of time to permit the pressure blocks of the machine to exert sufficient pressure against the box, using the adjustable form as an anvil to glue 55 these downturned edges of the paper to the inside of the box.

Heretofore when boxes of certain depths had to be made, a spacing block has been used to make up for the increased depth in the box, but this we overcome by the adjustabil- 60 ity of the presser plate through the medium of the rod 36 threaded into the stem 33 since by this arrangement, it is only necessary to back off the rod to the distance necessary to accommodate the presser plate to the 65 desired depth of box and then set up the nut

37 to hold the presser plate in this adjustment.

To provide for the convenient handling of boxes of considerable depth, we provide the angle wings 44 using four of such wings to take the place of the extension wings 40. 70 Each of these angle wings 44 has a shank 45 to which are secured the threaded studs 46 for passing through the slots 38, thus securing the angle wings in the same relative position to the presser foot as the extension wings are secured by tightening up upon the nuts 39a run upon said studs. 75

These angle wings supply the backing against which the sides of the box are forced when the rolls are acting upon said box in applying the finished paper thereto, as will be readily understood. 80

In order that the platen 43 may be adjustable to follow the adjustments of the presser plate, a bed plate 45a is secured to the spindle 46a of the machine which is normally held up by the spring 47 in the usual manner and this bed plate has superimposed thereon the slide plates 48, each having a stud 49 secured thereon. These studs pass through the rectangular openings 50 formed in the bed plate and have relatively large washers 51 thereon so that when the slide plates are adjusted to give the platen the desired dimensions, the setting up of the thumb nuts 52 will firmly hold these slide plates against displacement, as will be readily understood. 90

In the manufacture of boxes, our improved adjustable form is of great advantage in that it is rigidly supported upon a single suspension plate and from the further fact that in any adjustment no through and through break occurs on any side of the adjustable form, thus providing full and ample support to the box while being operated upon by the machine from the further fact that the presser plate by having the extension wings thereon may be adjusted to any size box being made and from the still further fact that provision is made for the various depth of boxes by the angle wings. Also one of the principle advantages of our invention is the adjustability of the presser plate relative to the adjustable form whereby the use of spacers are avoided. And further the adjustable platen provides for expanding this platen to correspond to the adjustments of the presser plate. 100

Of course we do not wish to be limited to the exact details of construction as herein shown, as these may be varied within the limits of the appended claims without departing from the spirit of our invention. 110

Having thus fully described our invention, what we claim as new and useful is:—

1. In a device of the character described, an expansion form comprising four angle sections, certain of said sections having tongues and certain of said sections having 120

grooves into which said tongues fit, the tongues being slotted for the passage of clamping screws and a suspension plate to which the angle sections are adjustably secured.

2. The herein described combination of an adjustable form for paper box making machines, of a presser foot, and means for so mounting said presser foot upon the machine

10 as to make it adjustable relative to the form.

3. In a form for paper box making machines, a suspension plate, an attachment block mounted upon said suspension plate, means carried by the block for attaching it

15 to the box machine, an adjustable form secured to said plate, an internally threaded stem adapted to pass through a central opening in said block, a rod threaded into the stem,

19 a presser foot secured to the lower end of the stem, and means for adjusting said presser

20 plate.

4. In combination with an expandible adjustable form of the character described, a presser plate so mounted as to coact with said

25 form and wings adjustably secured to the presser plate.

5. In combination with an adjustable presser plate of a machine of the character described, an adjustable platen comprising a

30 bed plate, adjustable sides superimposed upon the bed plate and means for holding said

slides in any adjustment.

6. In a machine of the character described, a platen comprising a bed plate mounted upon a spring cushioned spindle, and having relatively large openings therethrough; slide plates fitted against the upper surface of the bed plate; a threaded stud secured to each of said slide plates, said studs projecting through

40 said openings; washers carried by the studs and partially covering said openings; and thumb nuts threaded upon said studs for binding the washers and slide plate against the bed plate.

45 In testimony whereof, we have hereunto affixed our signatures.

CARL SCHWARZ.
PAUL PANHORST.
